US00D962285S

(12) **United States Design Patent** (10) Patent No.: **US D962,285 S**
(45) Date of Patent: **** Aug. 30, 2022**

(54) **DISPLAY SCREEN OR PORTION THEREOF WITH ICON**

(71) Applicant: **SAMSUNG ELECTRONICS CO., LTD.**, Suwon-si (KR)

(72) Inventors: **Gowoon Kim**, Suwon-si (KR); **Soojung Kim**, Suwon-si (KR)

(73) Assignee: **SAMSUNG ELECTRONICS CO., LTD.**, Gyeonggi-Do (KR)

(**) Term: **15 Years**

(21) Appl. No.: **29/770,720**

(22) Filed: **Feb. 16, 2021**

(30) **Foreign Application Priority Data**

Nov. 19, 2020 (KR) 30-2020-0056189

CLAIM

The ornamental design for a display screen or portion thereof with icon, as shown and described.

DESCRIPTION

The FIGURE is a front view of a display screen or portion thereof with icon, showing our new design.

The outer perimeter shown in broken lines in the drawings represents a display screen or portion thereof and forms no part of the claimed design. The dot-dashed broken lines define the boundary of the claimed design and form no part of the claimed design.
